METHOD AND APPARATUS FOR PRODUCING
GLASS FIBERSStuart M. Dockerty, Newark, Ohio, assignor to
Owens-Corning Fiberglas Corporation, a corpora-
tion of Delaware

Application September 12, 1939, Serial No. 294,487

21 Claims. (Cl. 49—1)

The present invention relates in part to a novel method and apparatus for producing fibrous material which may be either straight or undulated, and in part relates to novel types of crimped fiber and tangled or felted mats of crimped fibrous material. The invention is primarily designed for use in connection with the production of fibrous glass material but the same may also be found useful in connection with fibrous material composed of other thermoplastic materials which are extruded or flowed through an orifice.

The principal object of the invention is to provide a novel method of attenuating a glass stream issuing from an orifice associated with a glass feeder.

Another object of the invention is to provide such a method for producing glass fibers, together with an apparatus for carrying out the method, whereby in the event of interruption of stream flow, automatic resumption of attenuation will occur upon restoration of the stream flow, and thus obviate momentary shut-down during hand feeding of the fiber to the attenuating means.

Yet another object of the invention is to provide a method for producing fibrous glass in which any shot or other unfiberized particles issuing with the stream may be automatically segregated from the finished product.

A still further object of the invention is to provide an apparatus for producing fibrous glass by an attenuation process in which accumulated gobs or beads of glass, stone, or other foreign particles will pass through the apparatus unimpeded and will cause neither damage to the apparatus nor clogging thereof.

Another object of the invention is to provide such an apparatus which may be operated at high speeds and which has no moving parts that require synchronization with each other.

Another object of the invention is to provide such an apparatus which is relatively simple in its construction in that it has but a single moving part and therefore is unlikely to get out of order or otherwise require attention.

Another object of the invention is to provide an apparatus of this character which may be utilized in the production of either straight or undulated crimped fibrous glass at will by mere adjustment of the mechanical parts thereof, and/or the temperature of the molten glass, without resorting to substitution, addition or elimination of parts.

The objects of the invention thus far set forth are applicable to the production of either straight

or undulated fibrous glass. Where undulated or wavy crimped glass is concerned it has heretofore been difficult to achieve entanglement or felting of the crimped fibers for the reason that the nature of the crimping has been such that the undulations of the individual strands or fibers were not of a character that they could penetrate the undulations of adjacent strands or fibers and remain locked thereto permanently. Undulations heretofore produced generally were of the character of a sine curve and could generally be pulled from one another so that the product had neither cohesion nor mass integrity in any direction.

It is another important object of the invention therefore, where undulated fibrous glass is concerned, to provide a method of and apparatus for crimping glass fibers in such a manner that during the crimping process actual loops, as distinguished from mere undulations, are formed that close about one another and retain their form permanently so that the loops cannot readily be separated. This results in a product in which the fibers are definitely interlocked with one another and an exceptionally good degree of cohesion is attained.

Another object of the invention is to provide an apparatus by means of which the final crimp applied to the fibers occurs automatically in the suspended fibers themselves without the aid of any mechanical means and without any parts, moving or otherwise, touching the fibers during the formative stage.

Other objects of the invention not at this time enumerated will become apparent as the nature of the same is better understood.

In the accompanying drawings:

Fig. 1 is a sectional view, partially diagrammatic in its representation, of an apparatus for attenuating glass streams into fibrous glass;

Fig. 2 is a vertical sectional view taken transversely of Fig. 1;

Fig. 3 is a sectional view similar to Fig. 1 showing a modified form of apparatus;

Fig. 4 is a sectional view taken transversely through a crimping drum employed in connection with another modified form of the invention;

Fig. 5 is a sectional view similar to Fig. 4 showing another form of crimping drum;

Fig. 6 is a diagrammatic view of a forming apparatus by means of which the crimped glass fibers are formed into a mat;

Fig. 7 is a sectional view similar to Fig. 1 showing a modified form of crimping apparatus;

Fig. 8 is a vertical sectional view taken transversely and centrally of Fig. 7;

Fig. 9 is a sectional view similar to Fig. 1 showing an endless attenuating or crimping impeller employed in connection with a further modified form of the invention; and

Fig. 10 is a sectional view similar to Fig. 9, showing a still further modified form of crimping or attenuating impeller.

Briefly, the present invention contemplates the mechanical attenuation of fibrous glass streams by the coaction of a revolving or otherwise moving means and a gaseous jet adapted to direct the streams under the influence of such means to attenuate the same. It is also contemplated, if desired, to crimp the streams into wavy fibrous form of sinuous configuration. If the glass is sufficiently hot it may be projected, while still hot from the forming operation, into a quiescent atmosphere whereupon the preformed undulations in the fibers are transformed into partially closed loops which are capable of encircling one another to produce a mass of glass wool in which a relatively high percentage of interlocking between loops is effected.

Referring now to Figs. 1 and 2, the reference character 10 designates a glass feeding apparatus which may be of the type shown in the United States Patent No. 2,165,318. The feeder 10 includes a series of orifices 11 from which streams 12 of glass issue continuously. The temperature of the streams 12 as they emerge from the feeder may, if desired, be regulated by means of blowers 13 positioned beneath the orifices 11 in a manner similar to that disclosed in the Slayter and Thomas Patent No. 2,234,986. The blowers 13 may or may not be used according to the type of stream desired.

Spaced below the feeder 10 and positioned substantially tangential to the streams 12 issuing from the former is an irregular cylindrical surface or crimping drum 14 which is preferably of "squirrel cage" design and consists of a series of parallel crimping bars 15 arranged in cylindrical fashion and having their ends anchored in end plates 16 mounted on a central shaft 17. A spool-shaped spacing member 18 surrounds the shaft 17 and has its ends secured to the end plates 16. Any suitable means may be utilized for rotating the crimping drum 14, and as shown in Fig. 1, an electric motor M is adaptable for this purpose.

The streams or fibers 12 of glass issuing from the orifices 11 are directed tangentially against the crimping drum 14 by means of continuous lateral blasts of air issuing from a blower 19 through one or a plurality of superimposed series of jets 20 spaced apart a distance which will cause the blasts issuing therefrom to be directed simultaneously toward two or more adjacent interstices to crimp the streams or fibers 12 therein or at least to cause the streams to bear against the drum in such a manner that the frictional engagement between the drum and fibers will be sufficient to cause a definite gripping of the fibers to attenuate the streams issuing from the orifices 11.

The blowers 13 may be regulated to cool the fibers 12 to such an extent that little or no crimping will take place on the crimping bars 15 or, if crimping is desired, these blowers may be regulated to permit the fibers 12 to arrive at the crimping drum in a relatively hot state. In the latter instance, because the crimping drum 14

is rotating at relatively high speed, the relatively hot fibers 12 are crimped and thrown out tangentially of the drum by centrifugal force as indicated at 21. Inasmuch as the blasts are directed simultaneously into adjacent interstices in the drum 14, successive crimps formed by a single jet do not neutralize each other by taking up the slack of one another.

The crimped fibers shown at 21 are generally of sinuous wavy configuration inasmuch as this is the form imparted to them while they are operated upon by the blasts of air which force them against the moving crimping bars 15. If however the fibers as they leave the bars 15 have sufficiently low viscosity due to heat, a further crimping action may take place. Because of the high rate of surface speed of the drum 14, the fibers as they are thrown tangentially therefrom move longitudinally of themselves at terrific speeds in the neighborhood of from 4,000 to 50,000 feet per minute although other speeds may be employed. At these high speeds when the fibers have moved out of the range of air disturbance caused by rotation of the drum and/or the air disturbance caused by the blasts issuing from the blower 19 and have moved into a region of comparatively quiescent air, they bump or telescope, so to speak, into the quiescent air, are decelerated and pile up on each other to a certain extent so that loops 22 are formed. As the fibers are collected haphazardly in the form of bulk fibrous glass, some of these loops close about one another to a certain extent to form a partially felted body of wool that has tenacity or coherence in all directions.

The crimped fibers 21 may be passed through an opening 23 provided in a table 24 upon which for convenience the motor M may be mounted.

The crimped fibrous glass may be collected as it is formed upon a continuously moving surface or conveyor 25 (Fig. 6). Interfelting of the crimped fibers may be further enhanced by means of rollers 26 which operate upon the fibrous material to cause these so-called closed loops to penetrate one another and hook onto one another to produce a matted product that possesses exceptional tenacity in all directions and which, in order to be separated, must actually be pulled or torn apart. The rolls 26 may be driven in such a manner as to facilitate passage of the matted product therebeneath and also, if desired, they may be reciprocated longitudinally in order that the material may be thoroughly worked to produce a maximum amount of interfelting. A number of felting procedures are shown in the Slayter Patent No. 2,206,059, dated July 2, 1940.

It is to be noted that in the attenuation process wherein the streams or fibers 12 are actually drawn from the bottoms of the orifices 11, any stones, lumps or other unfiberized particles issuing from the orifices will be discharged by centrifugal force shortly after they have contacted the drum while the fibers 12 are carried further around the circumference of the drum than are the unfiberized particles. In order to collect these latter unfiberized particles and conduct them from the apparatus, a chute 27 extends beneath the drum as shown in Fig. 1.

In Fig. 3 a modified form of apparatus for merely attenuating the fibers 12 without substantially crimping the same is shown. In this form of the invention the attenuating drum 114 is shown as being driven by means of a turbine T. A blower 119 utilizing a single slot or series of jets 120 which is made adjustable as to size by

means of an adjustable plate 127 directs blasts of air substantially tangentially against the drum 114 to maintain the fibers in frictional contact with the drum in order that attenuation thereof may be effected. Ordinarily only a small pressure of about one-half to two or three pounds per square inch of air is required to maintain the streams or fibers 112 in engagement with the drum 114.

Inasmuch as the blast or blasts of air issuing from the jet or jets 120 are directed more or less tangentially of the drum 114, the fibers in leaving the drum continue to move in the path of air disturbance as created by the jets 120 and consequently they are not flung suddenly into any region of quiescent air and therefore they are not telescoped in the manner previously described in connection with the apparatus of Fig. 1. The net result of this is to produce fibers which are either very slightly crimped or which are substantially straight.

By inclining the blower 119 so that the jet or jets 120 approach a radial direction, crimps of a progressively deeper nature may be effected in the fibers. In this form of the invention, the fibers on leaving the drum are projected into more quiescent air.

In Figs. 7 and 8 a suction box within the drum has been employed for the purpose of creating a partial vacuum on the inside of the drum in the tangential region where the fibers engage the latter. The blowers of the previously described form of the invention may be omitted, if desired, and the rarified atmosphere within the drum in this region is relied upon to draw the fibers against or between the interstices of the crimping bars and perform the attenuating and, if desired, the crimping operation.

Accordingly, the drum 214 is mounted upon a hollow stationary shaft 217 which is formed with a series of apertures 241 within the drum that communicate with the interior of a suction box 242 mounted thereon by means of supporting spider arms 243. A driving motor M' is provided with a drive shaft 244 into which one end of the shaft 217 extends and which is keyed as at 245 to one of the end plates 216 of the drum. The other end of the shaft 217 is connected by means of a suitable flexible conduit 246 with a source of vacuum.

The outer or forward end of the suction box 242 is curved to accommodate the curvature of the drum and is open and fits closely against the drum in the tangential region where the drum is contacted by the stream 212 issuing from the orifices 211. Suction within the box 242 is relied upon solely for drawing the straight streams or fibers 212 into the interstices between the crimping bars 215 to force the same against the drum and effect attenuation thereof and, if desired, to crimp the same. The crimping operation may be augmented by the use of a blower similar to that illustrated at 19 in Fig. 1 or at 119 in Fig. 3.

In Figs. 4 and 5 crimping drums 314 and 414 having modified forms of crimping bars or ribs 315 and 415 respectively are shown. In the former instance the crimping bars 315 are in the form of flat ribs arranged uniformly at slight angles to each other and spaced about the periphery of the drum and slanting outwardly in the direction of rotation of the drum in such a manner that the streams or fibers which are blown, drawn or otherwise forced into the interstices between the crimping ribs may readily emerge therefrom. This form of drum is useful

in connection with a blower of the type shown in Fig. 1 at 19 inasmuch as the blasts of air directed radially into the drum will give an impetus to the slanting vanes tending to rotate the same. In Fig. 5 the flat crimping ribs 415 are radially disposed about the periphery of the drum, thus rendering a blower of the type shown in Fig. 3 at 119 adaptable for use with this type of crimping drum. It is obvious that either type of blower may be employed with either type of drum or, if desired, the suction box of Figs. 7 and 8 may be incorporated with these drums.

A somewhat more convenient method than that shown in Figs. 7 and 8 of partially vacuumizing the interior of the drum 514 is shown in Fig. 9 wherein a suction box 542 has an open forward end 547 shaped to partially encircle the drum 514, leaving a tangential region 548 against which the fibers 512 may be forced by the action of one or more blasts of air issuing from a blower 519. The blower 519 may however be omitted and suction within the drum 514 relied upon solely for drawing the fibers against the drum.

In Fig. 10 there is shown an endless attenuating or crimping impeller 614 which may be employed in lieu of any of the various attenuating or crimping drums previously described. The impeller 614 includes a pair of sprocket chains one of which is shown at 615 and which are mounted upon sprocket wheels 616 and across which there extend a plurality of spaced crimping bars 617 designed to operate upon the fibers 612 in the manner previously described in connection with any of the other forms of the invention. A blower 619 may be employed for directing blasts of air against the streams 612 to force the same against the crimping bars 615, or if desired, a suction box 642 that operates in the manner of the suction box 242 of Figs. 7 and 8 may be employed to draw the fibers into engagement with the crimping bars 615. Under certain circumstances it may be deemed advisable to employ both the suction box 642 and the blower 619. The blower 619 may also be directed more nearly tangentially to the sprocket 616 as shown in Fig. 3.

The invention is not to be limited to the exact arrangement of parts shown in the drawings or described in this specification as various changes in the details of construction may be resorted to without departing from the spirit of the invention. Various other materials of either an inorganic or an organic nature may also be attenuated by means of the present invention as for example, artificial silk, "Nylon," vinyl acetate, cellulose acetate, resins, sugar, etc. Moreover, the illustration of the fibers, especially as they are being crimped is diagrammatic since it is almost impossible to depict these fibers as they move at such great speeds.

Modifications and variations may be resorted to within the spirit and scope of the invention as defined in the appended claims.

I claim:

1. The method of producing crimped fibrous glass which comprises flowing a stream of molten glass into tangential contact with a cage comprising an annular series of parallel bars and revolving at high speed and directing an air jet against said stream and bars to cause tractive engagement therebetween.

2. The method of producing crimped fibrous glass which comprises flowing a stream of molten glass into tangential contact with a cage comprising an annular series of parallel spaced bars

and revolving at high speed while simultaneously directing a blast of a gaseous medium against the stream in a direction to force the same against said bars and loopwise into the spaces between the bars.

3. The method of producing crimped fibrous glass which comprises flowing a stream of viscous glass into tangential contact with a cage comprising an annular series of equally spaced crimping bars and revolving at high speed while simultaneously directing against the stream blasts of air in a direction substantially radial to the series with the blasts spaced apart a distance equal to the distance between adjacent bars to force the stream against the bars and between adjacent bars.

4. The method of producing crimped fibrous glass which comprises flowing a stream of viscous glass into tangential contact with a cage comprising an annular series of spaced parallel crimping bars and revolving at high speed while simultaneously directing blasts of air against said stream in a direction to force the same against said bars and between adjacent bars.

5. The method of producing a crimped glass fiber which comprises projecting a fiber of substantial sinuous configuration while it is still sufficiently hot from its forming operation to permit permanent deformation thereof into a quiescent atmosphere longitudinally at a sufficient rate of speed to cause the undulations thereof to pile up on each other and increase their magnitude.

6. The method of producing a crimped glass fiber which comprises projecting a fiber of substantial sinuous configuration while still sufficiently hot from its forming operation to be plastic into a relatively quiescent atmosphere longitudinally at a sufficient rate of speed to cause the undulations thereof to pile up on each other to an extent increasing the magnitude of the undulations to greater than a semicircle.

7. The method of producing a crimped glass fiber which comprises flowing a stream of viscous glass into tangential contact with a cylinder made up of an annular series of spaced parallel crimping bars and moving at a surface speed greater than the speed of stream flow, and establishing a differential air pressure on the inner and outer side of the series of bars to force the stream against said bars and between adjacent bars in the region of contact between the stream and the bars.

8. Apparatus for producing crimped glass fibers comprising a drum having spaced slots in its surface, means for revolving said drum about an axis, means for flowing a continuous stream of molten glass against said drum positioned relative to said drum to cause said stream to contact the drum in substantial tangential relationship and means for directing a current of air toward the drum at a stationary localized area and against said stream in the vicinity of the drum.

9. Apparatus for producing glass fibers comprising a foraminous drum, means for revolving said drum about an axis, means for flowing a stream of molten glass against said drum in substantial tangential relationship thereto, means for directing a current of air toward the drum and against said stream in the vicinity of the drum, a shield in the vicinity of the drum for restricting the field of air disturbance caused by rotation of the drum, there being an opening through the shield through which the stream passes after it has passed the drum.

10. In an apparatus of the character described, a crimping drum against which a stream of molten glass is adapted to be pressed to produce a crimped glass fiber, said drum comprising spaced end plates, and an annular series of crimping bars extending between the end plates in parallel relationship, means for rotating said drum, and means for creating a differential air pressure between the inside and outside of said drum at a localized area stationary relative to the drum to force fibers against said drum and thereby be attenuated.

11. The method of producing fibrous glass which comprises flowing streams of molten glass into tangential contact with an annular foraminous surface moving rotatively at high speed, causing tractive engagement between the streams and the surface by simultaneously directing blasts of a gaseous medium against the streams in a direction substantially tangential to the annular surface to force the streams against said surface, thereby attenuating the streams into fibers, and causing the fibers after leaving said surface to be carried in the path of air disturbance created by said blast.

12. The method of producing fibrous glass which comprises flowing streams of molten glass into tangential contact with an annular foraminous surface moving rotatively at high speed, causing tractive engagement between the streams and the surface by directing an air jet against said streams and surface in a region stationary relative to the movement of said foraminous surface to hold the streams against the surface and thereby attenuate the streams into fibers, and then causing said fibers to fly freely through the atmosphere and be deposited on an arresting surface.

13. The method of producing crimped fibrous glass which comprises flowing streams of molten glass into tangential contact with an annular slotted surface moving rotatively at high speed, simultaneously directing a blast of air against said streams in a direction to force the same against said surface and into the slots thereof to attenuate the streams into fibers of substantially wavy configuration, projecting the fibers while still hot from their forming operation in the general direction of their length away from said annular surface, and causing a deceleration of the lengthwise moving fibers at a rate sufficient to cause the undulations thereof to pile up on each other and increase their magnitude.

14. The method of producing crimped fibrous glass which comprises flowing streams of molten glass into tangential contact with a cylinder comprising an annular series of spaced bars and moving rotatively at high speed, simultaneously directing blasts of air against said streams in a direction to force the same against said bars and into the spaces between adjacent bars to attenuate the streams into fibers of substantially sinuous configuration, projecting the fibers while still hot from their forming operation into a relatively quiescent atmosphere longitudinally at a sufficient rate of speed to cause the undulations thereof to pile up on each other and increase the magnitude of at least some of the undulations, and then causing said crimped fibers to be deposited on an arresting surface in the form of a felted mass.

15. The method of producing crimped fibrous glass which comprises flowing a stream of molten glass into contact with a surface formed of a series of spaced bars, moving the surface in its

plane at high speed in the general direction of stream flow, causing tractive engagement between the stream and said surface by directing a gaseous blast against the stream in a direction to force the same against the surface and into the spaces between the bars to attenuate and crimp said stream.

16. The method of producing fibrous glass which comprises applying an attenuating tensile force to a stream of molten glass flowing from a source of molten material by causing said stream to contact a foraminous surface, establishing differential gaseous pressure on opposite sides of said surface at the area of contact between said stream and said surface to force the stream against the surface, and moving said surface at high speed relatively to the area of differential pressure and in a direction parallel with said surface and generally away from said source of molten material.

17. Apparatus for producing crimped glass fibers comprising a movable member provided with an endless perforate surface, means for moving said member in a direction to cause a portion of the said surface to move in a plane, means for flowing a stream of molten glass against said portion and in the general direction of movement of the surface in the region of contact between surface and stream, and a blower stationary relative to the movement of the surface of said member for directing a current of gaseous medium toward said portion and against said stream.

18. Apparatus for producing crimped glass fibers comprising a drum, the surface of said drum being formed of an annular series of spaced bars, means for revolving said drum about an axis, means for flowing a stream of molten glass against the surface of said drum in substantial tangential relationship thereto, a blower directed

toward the axis of the drum for directing a current of air toward the drum and against said stream in the vicinity of the drum.

19. Apparatus for producing glass fibers comprising a foraminous drum, means for revolving said drum about an axis, means for flowing a stream of molten glass against said drum in substantial tangential relationship thereto, a relatively stationary blower directed toward the drum 10 in substantially tangential relationship with the surface thereof for directing a current of air against said stream in the vicinity of the drum, thereby forcing said stream against said drum to attenuate said stream into a fiber and serving 15 to convey the fiber away from the drum.

20. In an apparatus of the character described, a crimping drum against which a stream of molten glass is adapted to be pressed to produce a crimped glass fiber, said drum comprising an 20 annular series of crimping bars extending across the drum in parallel relationship, and means for creating a differential air pressure between the inside and outside of said drum at a localized area to force fibers against said drum and be attenuated thereby, said area of differential air pressure being stationary relative to the drum.

21. Apparatus for producing crimped glass fibers which comprises an attenuating drum having a foraminous annular surface, a blower directed toward said drum to cause a blast of air to pass through said surface, means for rotating said drum relative to said blower whereby the annular surface moves past said blower, and means for flowing a stream of molten glass into 30 tangential contact with said drum in the region of coaction between said blast and said annular surface.

35 STUART M. DOCKERTY.
